CLAIM

The ornamental design for a magnetic resonance imaging device, as shown and described.

DESCRIPTION

FIG. 1 is a front perspective view of a magnetic resonance imaging (“MRI”) device, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a cross-sectional view thereof, taken along line 9-9 in FIG. 2.

The broken lines illustrating portions of the MRI device are for environmental purposes only and form no part of the claimed design.
